UNITED STATES PATENT OFFICE.

WALTER L. STRONG, OF SAN FRANCISCO, CALIFORNIA.

PROPELLER-WHEEL.

SPECIFICATION forming part of Letters Patent No. 378,221, dated February 21, 1888.

Application filed December 22, 1887. Serial No. 258,771. (No model.)

To all whom it may concern:

Be it known that I, WALTER L. STRONG, of the city and county of San Francisco, State of California, have invented an Improvement in 5 a Propeller-Wheel; and I hereby declare the following to be a full, clear, and exact description of the same.

My invention relates to an improvement in screw-propellers.

10 It consists of spirally-formed blades or vanes extending radially outward from the hub which is to be attached to the propeller-shaft, and in combination therewith of an exterior band or ring cast with or secured to the edges 15 of the propeller-blades and inclosing the front edges of the propeller-blades, while the rear ends are allowed to project beyond and behind this ring, as will be more fully explained by reference to the accompanying drawing, in 20 which the figure is a view of my propeller.

25 A is the hub of the propeller, which is secured to the propeller-shaft in any suitable or usual manner; and B are the blades, which may be two or more in number, and extend radially outward from the hub, having any desired pitch or form which will produce the best result in speed. These blades I have shown made of very considerable length from front to rear, and upon the outer periphery of the front portion 30 of the blades is cast or secured a broad hoop or band, C. This hoop or band is made as thin as is consistent with the necessary strength, so as to offer but little resistance as it passes edgewise through the water, and it 35 incloses the forward part of the propeller-

blades. In the present case I have shown this hoop as covering about two-thirds of the outer edges of the blades from front toward the rear. The rear one-third of the blade extends behind this hoop, as shown.

40 The operation of this device will be as follows: The hub, forming a part of the propeller and rotating with it, holds the water and prevents it from being thrown outward by the rapid revolution of the propeller, and thus 45 gives it a strong hold on the water, keeping the latter also a solid body and preventing its being churned up, and also serving to give it impulse directly back and in the line of travel of the boat. By leaving the rear portion of 50 the propeller-blades uncovered it allows the water to escape freely and discharge from the propeller without choking.

Having thus described my invention, what I claim as new, and desire to protect by Letters 55 Patent, is—

The propeller consisting of the hub and spirally-disposed blades projecting radially therefrom, in combination with the hoop or band secured to and inclosing the forward portion 60 of the blades, while the rear portion of the blades are inclosed and extend rearwardly from the hoop or band, substantially as herein described.

65 In witness whereof I have hereunto set my hand.

WALTER L. STRONG.
